UNITED STATES PATENT OFFICE.

WILLIAM L. GOULD, OF ALBANY, NEW YORK.

SURGICAL APPLIANCE.

Application filed March 13, 1925. Serial No. 15,239.

My invention relates to surgical or medical appliances and particularly to extension devices for use in applying tension to various parts of the body of a patient.

5 The use of extensions in the treatment of fractures, dislocations, and the general stretching of nerves and muscles, is well known to physicians. While apparatus is in general use, by which the direction and intensity of the tension may be varied to some extent, so far as I am aware, there is no apparatus by which gradual and positive variations in tension may be effected, or, in which gradual and positive variations in 10 the direction of the tension may be effected without substantially varying the intensity thereof.

The objects of my invention therefore, are to provide a device of this character in which 20 positive and gradual variations in the direction of the tension may be effected. Another object is to provide a device in which gradual and positive variations in the intensity of the tension may be effected. A further 25 object of my invention is to provide a device of this character in which gradual and positive variations in the direction of the tension may be effected without substantially varying the intensity thereof. A still further 30 object of my invention is to provide a device of this character which may be clamped in any position or at any place upon an operating table, the bed of a patient, or any other place.

35 With these objects in view my invention consists in the novel elements, and arrangements thereof as hereinafter described and which are shown in their preferred form in the accompanying drawings in which—

40 Fig. 1 is a side elevation of my device showing its application to a patient;

Fig. 2 is an elevation of my device viewed from the side toward the patient;

Fig. 3 is a side view of my device;

45 Fig. 4 is a bottom view of Fig. 3;

Fig. 5 is an enlarged top view of a fragmentary portion of Fig. 3;

Fig. 6 is a section of Fig. 5 on the line 6—6;

50 Fig. 7 is a view of a crank used in operating my device;

Fig. 8 is an enlarged section of my device on the line 8—8 of Fig. 3.

55 My device comprises a supporting member, 1, which preferably consists of a T-shaped plate portion, 2, adapted to be clamped to a

bed or other object by the clamps, 3, as shown in Figs. 1 and 2. Preferably integral with the T-shaped plate is the portion, 4, having a hollow, cylindrical bearing, 5. 60 Mounted in this bearing is the short, hollow, stub shaft, 6, which is preferably integral with, and is angularly disposed to the pulley carrying member, 7. Mounted in the pulley carrying member, 7, is the screw or worm, 8, which may be rotated by applying the crank shown in Fig. 7 to the squared end, 9, on said worm. Pulley, 10, is pivotally mounted on a block, 11, which is threaded to receive the worm, 8, and which fits between 65 and is prevented from turning by the portions, 12, of the pulley carrying member. Thus by rotating the worm, 8, the pulley may be moved along the worm and variation in the distance between the pulley and the 70 stub shaft, 6, may be positively and gradually effected by this means. Furthermore, because of the low pitch of the worm or screw, 8, no movement of the pulley can be effected by any load imparted thereto from 75 the cable, 32, and in this way, the system is 80 irreversible.

Mounted upon the pulley carrying member, 7, near the stub shaft, 6, is a second pulley, 13. This pulley is fixed in position 85 and is so placed that the axis of the stub shaft is substantially tangent to the lower surface thereof. The stub shaft, 6, extends through and projects beyond the hollow bearing, 5; as shown at 14, in Fig. 6. 90 Mounted upon this projecting portion of the stub shaft, 6, is the worm wheel, 15, which is secured thereto by means of the set-screw, 16. Meshing with the worm wheel, 15, is the worm, 17. The worm, 17, is formed upon a 95 hollow shaft, 18, into which is inserted a solid shaft, 19, provided with the squared ends, 20. The shaft, 19, is provided with bearing surfaces in the members, 21, which are preferably integral with the supporting 100 member, 1. The squared ends of shaft, 19, are adapted to receive the crank shown in Fig. 7, and, it is obvious that by turning the crank, 7, the stub shaft, 6, may be rotated in the bearing, 5, and thus swing the 105 pulley carrying member, 7, about the stub shaft as an axis. It will also be obvious that gradual and positive movements of the pulley carrying member may be thus effected.

Mounted upon the supporting member, 1, 110 beyond the projecting end of the stub shaft, are the pulley, 22, and the winding drum,

23. The winding drum, 23, is hollow, and receives the solid shaft, 24, provided with the squared ends, 25, adapted to receive the crank illustrated in Fig. 7. The drum, 23, is secured to the shaft, 24, by means of the set-screw, 26, and the shaft, 24, is provided with bearings in the members, 40, which are preferably integral with the support, 1. Attached to the drum, 23, or the shaft, 24, is 10 the ratchet wheel, 27. The pawl, 29, cooperates with the ratchet wheel, and is held in engagement therewith by means of the tension spring, 30. The pulley, 22, and the drum, 23, are so mounted that the axis of 15 the stub shaft is substantially tangential thereto, although they are separated sufficiently to permit a layer or two of cable to be wound upon the drum without interfering with the pulley. The drum, 23, is 20 provided with a small passage, 31, through which the end of the cable may be passed and secured by knotting or otherwise.

The operation of my device will be understood from a consideration of the detailed 25 drawings, and the general illustrations in Figs. 1 and 2. A cable, 32, which is adapted to be attached to the limb, 33, of the patient, as shown in Fig. 1 is passed around the pulley, 10, the pulley, 13, through the hollow stub shaft, 6, and, where a fixed tension 30 is desired, is attached to a weight, 34. Where a variable tension is desired, a weight is not used, but the end of the rope is secured in the passage, 31, of the drum, 23, and the 35 tension is obtained by winding the cable upon the drum. In either case, assuming a certain definite tension upon the cable, 32, it is obvious that the direction of the pull upon the limb of the patient may be gradually and positively varied by turning worm, 40 17. This operation will rotate the pulley carrying member in the bearing, 5, and, since a portion of the cable, 32, is substantially coaxial with the stub shaft, 6, there will be 45 no tendency to change the length of the cable and hence no substantial variation in the tension upon it. Where the weight, 34, is used to provide a fixed tension, it is obvious that in addition to changing the direction of 50 the tension upon the limb of the patient by means of worm, 17, the direction of the tension may be varied by operating the worm, 8, without, in any way affecting the intensity 55 of the pull on the cable. On account of the very slow and positive motion which may be effected by means of the worms, it is clear that extremely delicate adjustments may be made both in the direction and in the intensity of the pull either separately 60 or concurrently. Furthermore, since my device is essentially a single, compact unit, it may be readily transported from place to place and may be clamped to any convenient object thus enabling the surgeon to utilize 65 it in almost any emergency.

It is also obvious that while I have illustrated the T-shaped plate, 1, with its cross bar at the bottom, the pulley carrying member, 7, may be rotated 180 degrees and the stem of the T-shaped portion used for clamping in position instead of the cross bar.

While I have described my invention in its preferred embodiment I do not desire to limit myself to the precise details or illustrations thereof shown in the accompanying drawings or described herein. It is therefore to be understood that the words which I have used in describing my device are words of description and not of limitation, and that changes, within the scope of the appended claims may be made without departing from the spirit of my invention.

What I claim is:

1. A surgical extension apparatus comprising a clamping plate, a bearing associated with said plate, a shaft in said bearing having a pulley carrying member angularly disposed thereto, means for adjusting the distance between said shaft and pulley, and means for rotating said shaft in its bearing; 90 said mechanism being positively held in adjusted position.

2. A surgical extension apparatus comprising a clamping plate, a bearing associated therewith, a shaft in said bearing having a pulley carrying member angularly disposed to said shaft, means for varying the distance between said pulley and shaft, and means for rotating said pulley carrying member about the axis of said shaft.

3. A portable, surgical extension apparatus comprising a supporting means, a pulley carrying means revolvable about a substantially horizontal axis associated with said supporting means, and means associated with the carrying means for adjusting the distance between the pulley and the supporting means.

4. A surgical extension apparatus comprising a supporting means, a pulley carrying means rotatably associated therewith, means coacting with said carrying means for adjusting the distance between the pulley and the supporting means, and means cooperating between the pulley carrying means and the supporting means for effecting a relative rotative movement.

5. In a surgical extension apparatus, an axially mounted, pulley carrying member provided with means coacting therewith for positively and gradually varying the distance between the pulley and the axial mounting.

6. In a surgical extension apparatus, a pulley carrying member, a support therefor, a winding drum on said support, for varying the tension on a cable extending over a pulley on said member and adapted to be attached to the limb of a patient, and means for gradually and positively varying

- the direction of the tension upon the limb without substantially varying its intensity.
7. A surgical extension apparatus comprising a support, a pulley carrying member, means for varying the tension on a cable extending over a pulley on said member and adapted for attachment to a patient's limb, means for gradually and positively moving the pulley carrying member relative to said support without substantially varying the tension in said cable, and means independent of said first mentioned means for gradually and positively varying the tension on said cable.
- 15 8. A surgical extension apparatus comprising a support, a pulley carrying member rotatably associated therewith, a worm on said support coacting with a wheel on said member for effecting minute relative movements of said member and support; and a second worm coacting with a nut in said member for effecting minute variations in the distance between said support and a pulley on said member.
- 25 9. In a surgical extension apparatus, the combination with means for applying tension to the limb of a patient, of means for gradually and positively varying the direction of said tension without varying its intensity.
- 30 10. In a surgical extension apparatus, the combination with means for applying variable tension to a limb of a patient, of means for gradually and positively varying the direction of said tension through a wide angle and simultaneously varying its intensity.
- 35 11. In a surgical extension apparatus, the combination with means for applying ten-
- sion to the limb of a patient, of means for gradually and positively varying said tension and means for gradually and positively varying the direction of said tension.
12. In a surgical extension apparatus, the combination with means for applying tension to the limb of a patient, of means for gradually and positively varying the direction of said tension in a plurality of directions.
13. A surgical extension apparatus comprising a plate adapted to be clamped against a vertical surface, a horizontal bearing in said plate, a pulley, a carrying member for said pulley having an angularly disposed shaft adapted to fit within said bearing and means for gradually and positively rotating said shaft in said bearing.
14. A surgical extension apparatus comprising a plate adapted to be clamped against a vertical surface, a horizontal bearing on said plate, a pulley, a carrying member for said pulley having an angularly disposed shaft fitted within said bearing, means for gradually and positively rotating said shaft in said bearing, and means for gradually and positively varying the distance of said pulley from said shaft.
15. A surgical extension apparatus comprising a plate adapted to be clamped against a vertical surface, a horizontal bearing on said plate, a pulley, a carrying member for said pulley having an angularly disposed shaft mounted in said bearing and means for gradually and positively varying the distance of said pulley from said shaft.
